STEREOPHONIC HEAD SET

Sidney Becker, Woodbury, N.Y., assignor to Stanton
Magnetics, Inc., Plainview, N.Y.

Filed Sept. 30, 1971, Ser. No. 185,468

Term of patent 14 years

Int. Cl. D14—01, 03
U.S. Cl. D26—14 H

FIG. 1

FIG. 2

FIG. 1 is a perspective view of the stereophonic head set showing my new design; and

FIG. 2 is a side elevational view of the stereophonic head set of FIG. 1.

Having thus described the invention, I claim:

The ornamental design for a stereophonic head set, as shown.
